(57) **CLAIM**

The ornamental design for a cord holding assembly, as shown and described.

DESCRIPTION

FIG. 1 is an isometric view of a cord holding assembly showing my new design;

FIG. 2 is another isometric view of the cord holding assembly of FIG. 1;

FIG. 3 is a front view of the cord holding assembly of FIG. 1;

FIG. 4 is a rear view of the cord holding assembly of FIG. 1;

FIG. 5 is a first side view of the cord holding assembly of FIG. 1;

FIG. 6 is a second side view of the cord holding assembly of FIG. 1;

FIG. 7 is a top view of the cord holding assembly of FIG. 1; and,

FIG. 8 is a bottom view of the cord holding assembly of FIG. 1.

In addition, the surface shading illustrated in the figures is provided merely to highlight the contour of design and is not intended to be illustrative of texture or gloss.
